JAMES R. BALSLEY, OF NEW YORK, N. Y., ASSIGNOR TO FOX CASE CORPORATION, OF NEW YORK, N. Y., A CORPORATION OF NEW YORK

APPARATUS AND METHOD FOR COPYING PHOTOGRAPHICALLY-RECORDED SOUND RECORDS

Application filed December 5, 1928. Serial No. 324,018.

This invention relates to a certain new and improved apparatus and method for copying a photographically recorded sound record.

Photographically recorded sound records 5 are of at least two types. First, a variable density record, and second, a variable area record, and the main object of this invention is the production of an apparatus by means of which an exact duplicate of the original 10 record, whether it be of the variable area or the variable density type, can be produced.

Further, the apparatus provides a means for producing an equivalent variable density record from a variable area original or for 15 producing an equivalent variable area record from a variable density original.

Further, the apparatus and method of this invention permits the production of more accurate copies or equivalents in that the film 20 upon which the record is to be produced may be run at comparatively low speed considerably below the natural period of the light valve used, and permits the use of simple light valves not suitable for high frequencies, 25 such as a common oscillograph element, or as here illustrated, a galvanometer.

Other objects and advantages relate to the details of the structure and the form and relation of the parts thereof, all as will more fully 30 appear from the following description taken in connection with the accompanying drawings, in which:—

Figure 1 is a diagrammatic illustration of an apparatus for producing a variable density record which is substantially the exact 35 duplicate or equivalent of either a variable density or a variable area original record.

Figure 2 illustrates a section of film provided with a variable area record.

Figure 3 is a similar view of a variable density record.

Figure 4 diagrammatically illustrates an apparatus for producing a variable area record substantially the exact duplicate or 5 equivalent of a variable area or a variable density record.

Figure 5 is a further diagrammatic illustration of a portion of an apparatus for producing a variable area record.

Figure 6 is a section of a film having a variable density record thereon.

Figure 7 is a section of a film having a variable area record thereon.

The system requires that the developed 55 original film and the unexposed film on which the copy is to be made should be run through the machine at exactly the same speed, and this may be accomplished as hereinafter described by moving the films by identical 60 sprockets on the same shafts or any other convenient means of synchronizing the parts.

As illustrated in Figure 1 the film —1— bears an original record of light variations corresponding to sound wave variations here- 65 in termed a sound record. Any suitable means may be provided for focussing or producing upon this film a line of light of a size and shape substantially identical with the size and shape of the line of light utilized 70 in the production of the sound record.

This straight beam of light may be produced as shown by focussing the rays of light from an electric lamp —2— upon a slit —3— in an opaque wall —4— as by means of lens 75 —5—. The slit —3— may, if desired, be of a different size than the desired line of light to which the film —1— is exposed, and its image may be either enlarged or reduced, as desired, by means of a lens or lens system 80 —6—.

There is here illustrated a wall —7— having a slit —8— therein past which film —1— moves in close relation with the slit but where suitable focussing means is provided, as here 85 illustrated, the opaque wall —7— with its slit of desired size is preferably omitted. The line of light striking the film —1— is modulated in accordance with the sound record upon the film as it is transmitted through the 90 film and falls upon the photo-electric cell or other light reactive element —9— included in circuit with the filament —10— and grid —11— of an electron discharge device —12—.

As illustrated, a resistance —13— may be 95 inserted across the source of potential —14— and the light reactive element —9— and a further resistance —14— and source of potential —15— may be inserted across the filament and grid of the electron dis- 100

charge device. A condenser —16— is positioned, as shown, if desired.

The output circuit of the electron discharge device —12— is connected through 5 any desired number of stages of amplification with a source of light —17—, a source of potential —48— being provided for maintaining the source of light in light-emitting condition.

10 This source of light may be in the form of a bulb —18— containing a pair of spaced electrodes —19— and —20— and a suitable ionizable gas such as helium or helium with a small percentage of nitrogen, the gas pressure being preferably such that at operating voltage an intense light is concentrated about the cathode, and this glow is the light utilized for producing a photographic record.

The light from this source of light —17— 20 passes through a narrow elongated slit —21— of the same size as the line of light to which film —1— is exposed, and falls upon the unexposed film —22—. As the film —22— is running at the same speed as the film —1— for the reason that sprockets —23— and —24— are driven at the same speed, and are of the same size, there will be produced upon film —22— a variable density sound record which is either identical 30 with the sound record upon film —1— if that record be a variable density one, or will be the exact equivalent for reproducing sound if the sound record upon film —1— is a variable area record.

35 In other words, the film —1— may include either the variable area record A of Figure 2, or the variable density record B of Figure 3, and in either case the variable density record B will be produced upon film —22— which is either an exact copy or a sound equivalent of the record upon the film —1—.

In Figures 4 and 5 an apparatus is disclosed for producing a variable area record which is either a copy or an equivalent of 45 a variable area or a variable density sound record. The film —1— in this disclosure may, as stated, include either the variable density record B of Figure 6 or the variable area record A of Figure 7. The means illustrated for focussing a line of light upon this film is the same as that disclosed in Figure 1, and the light reactive device —9— and its circuits to the galvanometer —30— may be the same as the circuits connecting light cell 50 —9— with the source of light —17—.

The structure of Figure 4 differs from that point in that a type of apparatus is shown illustrative of a means for producing a variable area sound record. In such case a mirror —31— may be attached for movement with the galvanometer shaft —32—. A source of a line of light is utilized, as for instance the straight line filament lamp —33—, the image of which filament is focussed by lens or 65 lens system —45— upon the mirror —31—,

and this mirror is so positioned with respect to a slit —43— in an opaque wall —44— as to reflect the line of light focussed upon it through said slit. Oscillation of mirror —31— in accordance with galvanometer variations conforming to electrical variations in the circuit leading from the light reactive device causes more or less of the length of the line of light to pass through the slit —33—, thereby producing a variable area sound record A, and in like manner, as described in connection with Figure 1, the film —22— moves past slit —43—, at the same speed as the film —1— moves past the slit —8—, the respective films being driven by 70 similar sprockets —23— and —24— mounted upon the same shaft.

75 It will be apparent that with this apparatus, the film —1— may be either a variable density sound record or a variable area sound record, and that in either case there will be produced upon film —22— a variable area record A, either an exact copy of a film —1— including a variable area record, or else a variable density record B will be produced upon film —22— which is the equivalent for sound production of the sound record upon the film —1—.

80 As before stated, an important feature of this invention resides in the fact that the films —1— and —22—, in order to make the copy or the equivalent record in accordance with this invention, can be run at a speed much slower than the speed at which film —1— was run in the production of the original record thereon, and as a result a simple light valve not suitable for high frequencies may be used, such as a common oscillograph element, an illustrative apparatus being here shown as a galvanometer and mirror actuated 85 thereby, and such light valve need not have a flat frequency characteristic above sixty cycles if 9000 cycles is the highest frequency to copy, and the copy is made at 1/150th, the speed at which the original record —1— was 90 made.

95 Altho no exact dimensions of the line of light to be focussed upon the films need be given, as considerable variation is possible, dependent upon film speed and frequencies to be copied, etc., yet this beam is preferably as narrow as practicable, and must be small compared to the length of the film covered by a half cycle of the highest frequency recorded on the original, for example:—

100 If 9000 cycles per second is the highest frequency desired on the copy and the original sound record was made on a film run at 90 feet per minute, one-half cycle will take up .001 of an inch of the length of the film. 105 The beam of light should then be less than .0003 of an inch wide.

110 Altho I have shown and described a specific apparatus and details of embodiments of the invention as illustrative of apparatus for 115

carrying out the same, I do not desire to restrict myself to the particular apparatus disclosed or to the details of form, arrangement or construction of the same, as various changes and modifications may be made within the scope of the appended claims.

I claim:

1. An apparatus for producing a photographic sound record comprising a film having a variable area sound record thereon, means for directing a line of light upon such record, a light reactive element exposed to the light transmitted through said record, a sensitized element and means for producing on said sensitized element a variable density sound record capable of exactly reproducing the sound photographed upon said film including a lamp adapted to emit light rays of variable intensity in accordance with variations in the light rays to which said sensitized element is exposed.

2. An apparatus for producing a photographic sound record comprising a film having a variable area sound record thereon, means for directing a line of light upon such record, a light reactive element exposed to the light transmitted through said record, a sensitized element, means for producing on said sensitized element, a variable density sound record capable of exactly reproducing the sound photographed upon said film including a glow lamp adapted to emit light rays of variable intensity in accordance with variations in the light rays to which said sensitized element is exposed, and means for moving said film and said sensitized element at the same speed.

3. An apparatus for producing a photographic sound record comprising a film having a variable area sound record thereon, means for directing a line of light upon such record, a light reactive element exposed to the light transmitted through said record, a sensitized element, means for producing on said sensitized element a variable density sound record capable of exactly reproducing the sound photographed upon said film including a glow lamp adapted to emit light rays of variable intensity in accordance with variations in the light rays to which said sensitized element is exposed, and means for moving said film and said sensitized element in synchronism at a speed substantially slower than the speed at which the film was moved when the sound record was produced on said film.

In witness whereof I have hereunto set my hand this 13th day of November, 1928.

JAMES R. BALSLEY.
